CATLINE APPARATUS FOR HOISTS

Filed May 13, 1941

FIG. 1.

FIG. 2.

Inventor:

AUGUST R. MAIER,
by: John E. Jackson
his Attorney.

UNITED STATES PATENT OFFICE

2,323,095

CATLINE APPARATUS FOR HOISTS

August R. Maier, Oil City, Pa., assignor to Oil Well Supply Company, a corporation of New Jersey

Application May 13, 1941, Serial No. 393,272

4 Claims. (Cl. 254—176)

My invention relates to improvements in catline apparatus for hoists of the character employed in drilling wells, wherein a pair of catlines are used, one for spinning the drill pipe as when making up joints, and a second for auxiliary hoisting purposes, each selectively operable from a single cathead.

In the first instance, the spinning rope extends laterally from the cathead around the driller's position at one side of the hoist to the drill pipe at the well, and in the second instance, a line extends from said cathead in an upward direction through a pulley or guide above the driller's position over the crown block of the derrick and thence downwardly to attachment with the work to be hoisted thereby. Due to the fact that both catlines must necessarily pass in close proximity to the driller's position at the hoist, they are a source of continuous hazard to the driller.

While projecting guides or protective devices may be provided for shielding the driller from such hazard, they generally present an additional problem due to their projection beyond the main hoist structure exceeding permissible road clearance dimensions. Likewise, such devices must be positioned in proper relation to the cathead for powering said catlines for efficient operation.

It is a prime object of this invention to provide a catline apparatus for a well drilling hoist which may be positioned in protective relation to the driller and in proper power-receiving relation to the cathead, which may also be disposed within the overall width of the hoist on which it is mounted, thereby insuring proper road clearance for a hoist otherwise within the legal limits prescribed therefor.

Further objects are to provide apparatus of the character stated which is readily applicable to existing hoists; to provide for the selective adjustment thereof in relation to the driller's position and the hoist; and to provide a positive and safe guard for the protection of the driller.

Additional objects and advantages will become apparent from the following description taken in connection with the accompanying drawing, wherein:

Fig. 1 is a top plan view of a well drilling hoist showing my invention applied thereto; and

Fig. 2 is an enlarged side elevational view of Fig. 1.

Referring to the drawing, A designates a well drilling hoist of well known construction, including a skid frame 2 upon opposite sides of which an upright frame 3 is supported for mount-

ing a drum shaft 4 and a line shaft 5. A jack shaft 6 is mounted on the skid frame and receives the applied power by a belt drive 7 from a suitable engine, and by means of chain drives, the power is transmitted between said shafts in the conventional manner, said engine and chain drives being omitted as the same are well known and are not a part of the present invention.

A rotary 8 is diagrammatically shown in Fig. 1 in positional relation to the hoist to clearly illustrate the location of the catlines with which the present invention is concerned, said rotary having its table 9 centered in the usual derrick over the hole or well.

In the drilling operation, it is frequently desirable to spin the drill pipe sections at the rotary, as by means of a spinning rope or catline 10 powered by a removable cathead 11 mounted on and driven by the line shaft 5 at one side of the hoist, generally that side of the hoist at which the driller stands, the driller's position being indicated by the circle X in Fig. 1.

For the purpose of guiding said catline about and protecting the driller, I provide a vertical roller 12 rotatably mounted in a pair of adjustable brackets 13 extending outwardly from the upright frame 3 on the driller's side of the hoist. Suitable horizontal bearing plates or members 14 are welded or bolted to said frame for mounting the roller brackets.

The brackets 13 are bolted outwardly of their inner terminals, as at 15, to their respective bearing plates 14, thereby providing a pivotal mounting for the brackets and roller for horizontal swinging movement thereof in relation to the hoist. Each bearing plate 14 is provided with a series of bolt holes 16 for selectively securing the inner terminals of the brackets by bolts 17 upon pivotal movement of the brackets about the bolts 15, thereby securing the roller in adjusted position.

Hence, the roller may be swung outwardly from the hoist side to position the same in operative relation to the cathead 11 secured to the line shaft, and in such position receive and guide the catline 10 about the driller without hazard to him during the operation of said catline.

Since a hoist of the character illustrated may be of substantial width, difficulty has been encountered by the use of former catline equipment, due to its projection beyond the hoist and beyond permissible road clearance. Equipment of the character described must be transported from one drilling site to another and must con-

form to the legal road clearance during such transportation.

I have mounted my improved catline guard roller in such a manner that it may be swung inwardly toward the hoist body as shown in dotted lines in Fig. 1, by pivotal movement thereof about the bolts 15, whereby the roller and its brackets lie inwardly of the side clearance plane a—a defined by other parts of the hoist. The pivot bolts 15 are located well within the road clearance limit of the hoist structure, and the width of the brackets 13 outwardly beyond said bolts is restricted to dispose the brackets within said limit or plane when moved inwardly toward the hoist body.

As a further feature of my catline apparatus, I provide a sheave 18 removably mounted upon the upper roller bracket 13 for receiving a second catline 19 from the cathead 11 for auxiliary hoisting purposes, said catline extending upwardly as to the crown block of the derrick. By locating the sheave 18 on said bracket, the said sheave is automatically disposed in operative relation to the cathead 11 when the roller 12 is positioned for operation, and due to the upper bracket 13 being elevated from the ground and above the level of the line shaft, the sheave serves to confine the catline 19 so as not to interfere with or endanger the driller, said line passing upwardly from said sheave into the derrick above the driller's head.

Various modifications are contemplated within the scope of the following claims.

I claim:

1. In a well drilling hoist having a supporting frame and including a projecting shaft, a cathead mounted on said shaft and projecting from the driller's side of the hoist, said cathead being readily removable from the shaft to provide road clearance, a catline guard disposed adjacent the driller's position including a vertical roller, means pivotally mounting said roller on the frame for horizontal swinging adjustment thereof, and means for securing the roller and its mounting in extended position in operative relation to the cathead, said mounting being proportioned and with the roller being movable to lie in retracted position within the outermost extent of the shaft for said cathead.

2. In a well drilling hoist having a supporting frame and including a projecting shaft, a cathead mounted on said shaft and projecting from the driller's side of the hoist, said cathead being

readily removable from the shaft to provide road clearance, a cathead guard adjustably mounted on said side of the frame between the cathead and the driller's position, said guard including a pair of vertically spaced brackets, a vertical roller supported therebetween, said brackets being pivotally secured to the frame for horizontal swinging movement for selectively positioning the roller in relation to the cathead and the driller's position, and means for securing the brackets in adjusted position, said brackets being proportioned and with said roller being movable to lie in retracted position within the outermost extent of the shaft for said cathead.

3. In a well drilling hoist having a supporting frame and including a projecting shaft, a cathead mounted on said shaft and projecting from the driller's side of the hoist, said cathead being readily removable from the shaft to provide road clearance, a catline guard adjustably mounted on said side of the frame between the cathead and the driller's position, said guard including a pair of vertically spaced brackets, a vertical roller supported therebetween, said brackets being vertically pivoted inwardly of the outermost part of the said cathead shaft, said brackets being so proportioned and with the roller being movable on said pivotal mounting into retracted position within the outermost extent of said shaft, or into extended position therebeyond to position the roller in relation to the cathead and driller's position, and means for securing the brackets in adjusted position.

4. In a well drilling hoist having a supporting frame and including a projecting shaft, a cathead mounted on said shaft and projecting from the driller's side of the hoist, said cathead being readily removable from the shaft to provide road clearance, a catline guard disposed adjacent the driller's position including a vertical roller, a pair of vertically spaced brackets pivotally mounting said roller on the frame for horizontal swinging adjustment thereof, means for securing the brackets with the roller in extended position in operative relation to the cathead, said brackets being proportioned and with the roller being movable to lie in retracted position within the outermost extent of the shaft for said cathead, and a sheave mounted on the upper bracket disposed to be positioned in operative relation to the cathead when the brackets and roller are in extended position.

AUGUST R. MAIER.
